INVENTOR.

ATTORNEY.

UNITED STATES PATENT OFFICE.

LOUIS J. VAN GELPEN, OF CINCINNATI, OHIO.

SHOE-RELASTING MACHINE.

Application filed July 22, 1921. Serial No. 486,843.

To all whom it may concern:

Be it known that I, LOUIS J. VAN GELPEN, a citizen of the United States, residing at the city of Cincinnati, in the county of Hamilton and State of Ohio, have invented certain new and useful Improvements in Shoe-Relasting Machines, of which the following is a specification.

My invention relates to new and useful improvements in means for lasting shoes, and it is more particularly directed to the provision of a machine for performing the second lasting operation on what is known as turned shoes, such shoes being lasted and stitched inside out, and then turned and subjected to a second lasting operation to impart their final shape thereto.

It is primarily the object of my invention to provide a machine whereby a shoe may be snugly fitted on the forward portion of the last in a most rapid and efficient manner, and without making unusual demands on the strength of the operator in contradistinction to the manual operation now employed of pounding the last against a table or other support to effect a snug engagement of the shoe thereon.

A further object of my invention is to provide a means for inserting a shoe on a last which does not require pounding of the last, with the consequent damage entailed thereby.

A still further object resides in the provision of a lasting machine adapted to perform the functions above set forth and which has its parts so arranged as to most readily receive a shoe and last for the operation of the machine, to procure economy of the operator's time and permit a most rapid operation of the machine.

With the above and other objects and advantages in view, which will be apparent as the description proceeds, my invention resides in the novel features of construction, combination and arrangement of parts as hereinafter more particularly described and defined by the appended claims, and it may be stated here that my present invention is an improvement on the invention shown, described and claimed in United States Letters Patent No. 1,312,676, dated August 12, 1919.

In the accompanying drawing forming part of this specification:

Fig. 1, is a view in elevation of a relasting

machine embodying my invention, parts being broken away,

Fig. 2, is a top view looking down upon the machine,

Fig. 3, is a top view of the cam, heel support mechanism and part of the toe pad, partly broken away,

Fig. 4, is a sectional view of the jaw member, the clamping member being shown in elevation.

Fig. 5, is a view in elevation of the jaw members and of part of the cam race in section,

Fig. 6, is a view in elevation of a horn and supporting block, to replace the jaws, when certain kinds of shoes are relasted, parts broken away, and

Fig. 7, is an end view of the parts shown in Fig. 6, parts broken away.

In the drawing the character 1 represents a table or support to which my machine is secured. I use a base and peculiarly shaped casting or frame made integral in the present instance and composed of a base 2, an upwardly and backwardly extending arm 3, a forwardly and upwardly extending arm 4 united by a curved connecting element 5, the curved top face of which forms a cam race 6; at the top of arm 3, I form a toe pad 7. The above parts are usually all formed integral.

On the top of the toe pad 7, I place a leather cushion 8 held on and in place by the rivets 9.

At the forward and lower portion of the arm 4 I loosely connect at point 10, a lever 12, and at the upper extremity of this lever I pivotally connect the jaw members 13 and 14, at pivotal point 15. To the forward portion of the lever 12, I connect a pull-rod 16, which at its forward end has pivoted thereto the pull rod 17; this rod 17 extends downwardly to be connected to any suitable foot treadle, (not shown). At the inner side of the lever 12, I connect one end of a spring 18, which at its other end is connected to arm 3, at the point 19.

On the opposite side of the arm 4, near the top, I place the bearing lugs 20 and 21 made integral with arm 4. Through these lugs I place the shaft 22, which shaft is slideable and oscillates. Between the lugs 20 and 21 on the shaft 22, at point 23, I rigidly connect the peculiarly shaped arm 24, shaped as shown, and at the back of this arm, around

the shaft 22, I place a push spring 25. In the top of the bearing 21 I place a slot 26 and the point 27 of arm 24, (when the lever or arm 24 is in its upward position) automatically engages in said slot 26, by reason of the push spring 25, operating to push said lever 24 into said slot, when the said slot is reached as the lever is oscillated. At the top of arm or lever 24 I place a grooved 10 or cup shaped heel support 28, which has, at its extreme top a cover or stop plate 29. At the bottom of said arm 24 I place a stop lug 30, which limits that sidewise movement or motion of said arm 24.

15 In the arm 4, I place a number of adjusting holes 31 in which I place a stop pin 32, which stops the movement of the lever 12 at the desired point.

At the lower portion or end of the movable clamping jaw member 14, I connect a ball weight 33, pivoted at point 34, in the jaw member 13. The upper portion of the jaw member 14 is an eccentric, as shown as point 35, in Figs. 1 and 4. These jaw members 13 and 14 are each provided with a multiplicity of holding or gripping teeth 36.

The last is marked 40 and the shoe 41. The above description and mechanism which refers to the jaws 13 and 14 and their operation is usually employed with shoes on which the heel or seat is left unsewed; when the heel or seat is also sewed, as is sometimes the case, I replace the jaws with the device shown in Figs. 6 and 7. In these figures I show a block 42 pivoted to the arm 12 at point 43; the block 42 being provided at the forward part with a lug 11. On the block 42 I place a hook or horn 44 of a desirable shape and contour. The means just described is for use with a shoe having the heel or seat also sewed, and when such means are used a hole is placed in the heel of the insole which engages with the hook 44. In operating, the heel support 28 is thrown to one side (to the left), as shown in Fig. 2; the shoe is then placed on the toe pad 7; the loose portion 50 of the sole, at the heel, is placed in between the jaws 13 and 14, the ball 33 being pulled towards the operator 45 closing the jaws and locking or gripping the sole therein; the last 40 is then inserted into the shoe 41 and is pushed forward and lined up in the shoe; the lever 24 is then thrown into an upright position as shown in Figs. 55 1 and 3; the operator then places his foot upon the treadle of the machine (not shown), and by giving a downward pressure pulls the lever 12 by means of the connecting link 17 and the attached arm 16, 60 forward, and this lever being fulcrumed at 10 and the jaws 13 and 14 being pivoted at 15, allows the lug 11 to ride the face 6 of cam 5 and by reason of the cam face being curved, when the shoe is pulled onto the 65 last by the lever 12 being pressed forward,

and the jaws still holding the shoe sole, a line is described which is approximately the same as the line on the last arch; this pulling the shoe from the toe out, and thus not binding the instep of the shoe on the instep of the last, (as has heretofore been the operation) thus giving a proper and desired contour to the shoe, the same as pulling the shoe on the foot. This cam face can be varied in contour to suit any shape of last. During this operation the heel support 28 and the heel of the last have been in engagement to keep the last from moving with the shoe, that is, in a stationary position, while the shoe is being pulled onto the last.

When the operator has pulled the shoe onto the last to the desired point or extent, he then works out the wrinkles and shapes the toe of the shoe with his tools and then takes his foot off of the treadle, the lever 12 then moves backward up against the stop pin 32, by reason of the spring 18, carrying the shoe and the last with it, the operator then pushes the ball 33 backwardly and disengages the sole from the jaws 13 and 14 and then takes the shoe from the machine, throws the lever 24 to the left and continues the same operation with another shoe.

It will be noted that I provide a number of holes 31 so that the pin 32 can be set in any of such holes so that different sizes of shoes can be more readily operated upon. When sewed seat shoes are being relasted on this machine, a hole is cut into the center of the seat or heel of the shoe, for engaging the horn or pin 44; this part replacing the function of the jaws 13 and 14, however the same operation of the machine is employed otherwise.

While I have described one specific means for carrying my invention into effect, it will be understood that the same is capable of some modification without departing from the spirit and principle of the invention as covered by the claims.

What I claim as new and my invention and desire to secure by Letters Patent is:

1. A relasting machine including means for affording stationary support for a last, and means movable with respect to said support means and engageable with the sole of the shoe mounted on a last on said support means for drawing the shoe on the forward portion of the last, and means for causing the means for drawing the shoe on the last, to move in a curved line substantially corresponding in contour to the portion of the bottom surface of the last which extends from the heel to the ball of the arch.

2. A relasting machine including a last heel support, capable of being moved and locked, a last sole support, and means movable below said support and engageable with the sole of a shoe mounted on a last seated on said supports for drawing the shoe on the

last; said supports holding the shoe in approximately a horizontal position, said means engaging with the sole, and capable of moving in a line to give a straight pull in drawing the shoe on the last.

3. A relasting machine including a last heel support, capable of being moved into and out of position, a last sole support, and means for engaging with the sole of a shoe 10 mounted on a last seated on said supports for drawing the shoe on the last, said means for drawing the sole on the last capable of moving in a curved line to draw the shoe on the last to prevent buckling of the leather 15 at the instep.

4. A relasting machine including a support on which a shoe and a last are adapted to rest, a swinging abutment pivotally connected to said support and adapted to engage the heel portion of a last, an oscillating lever, means for moving said lever in opposite directions, a sole engaging member pivotally connected to said lever, and a curved track of approximately the same 25 contour as the lower surface of the last, on which the gripping member slides when moved by said lever.

5. A relasting machine as claimed in claim 4 including adjusting means for limiting 30 the movement of the lever in one direction.

6. A relasting machine as claimed in claim

4 in which the abutment is fixed to an axially movable pivotally mounted rod, and resilient means for forcing said abutment in one direction.

35

7. A relasting machine as claimed in claim 4 in which adjustable means are provided for limiting the movement of the lever in one direction, and in which the abutment is forced in an opposite direction by resilient 40 means.

8. A relasting machine including a base, a bracket carried by said base, and having a cam track, a lever pivotally mounted on said bracket, a sole engaging member pivotally mounted on said lever and slidable along said track, automatic means for moving the lever in one direction, means to permit the operator to move the lever in an opposite direction, an axially movable rod 50 pivotally mounted on said bracket, an abutment fixed to said rod and adapted to be swung into a position to engage the heel portion of a last supported by said bracket, means for fixing said abutment in the position in which it engages said last, and a spring engaging said abutment for moving the same in a direction away from the last.

In testimony whereof, I affix my signature at Cincinnati, Ohio, this 16th day of July, 60 1921.

LOUIS J. VAN GUELLEN.
